United States Patent Office

Des. 183,176
Patented July 8, 1958

183,176

SINGLE SINK FAUCET BODY

René Mornard, St. Lambert, Quebec, Canada

Application September 26, 1957, Serial No. 47,876

Term of patent 14 years

(Cl. D91—3)

FIG. 1

FIG. 2

FIG. 3

Figure 1 is a side elevational view of a single sink faucet body, showing my new design;

Figure 2 is a top plan view of a faucet body; and

Figure 3 is a front elevational view of a faucet body.
I claim:

The ornamental design for a single sink faucet body, as shown.
